Primary Examiner — Messina L Smith*Assistant Examiner* — Aram Kwon(74) *Attorney, Agent, or Firm* — Kunzler Bean & Adamson, PC; Michael Bartholomew(57) **CLAIM**

The ornamental design for an interphone as shown and described.

DESCRIPTION

FIG. 1 is a front, right and top perspective view of an interphone, showing our new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2; and,

FIG. 11 is an enlarged view of detail 11 in FIG. 8.

The dashed broken lines depict portions of the interphone that form no part of the claimed design.

The dot-dash broken lines in FIGS. 1, 2, 8, 9, 10 and 11 depict the boundaries of the enlargements and form no part of the claimed design.

1 Claim, 11 Drawing Sheets(56)
